UNITED STATES PATENT OFFICE.

CHARLES A. ALDEN, OF STEELTON, PENNSYLVANIA.

RAILWAY-SWITCH MECHANISM.

1,099,232.

Specification of Letters Patent.

Patented June 9, 1914.

Application filed January 21, 1914. Serial No. 813,383.

To all whom it may concern:

Be it known that I, CHARLES A. ALDEN, a citizen of the United States, residing at Steelton, in the county of Dauphin and State 5 of Pennsylvania, have invented certain new and useful Improvements in Railway-Switch Mechanism, of which the following is a specification.

The object of my invention is to provide a 10 railway switch mechanism of novel, simple and efficient construction having provision, first, whereby, when the parts are set in one position, the switch tongue will be yieldingly maintained in a position against the track rail 15 of the switch structure and automatically returned thereto after being moved therefrom and released, secondly, whereby, when the parts are set in another position, the switch tongue will be yieldingly maintained in a position against the guard rail 20 of the switch structure and automatically returned thereto after being moved therefrom and released, thirdly, whereby, when the parts are set in a third position, the 25 switch tongue will be yieldingly held in either a position against the track rail or a position against the guard rail to which it may be moved, and, fourthly, whereby, when the parts are set in the last named position, the 30 yielding pressure against the switch tongue will be greater than when the parts are set in either of the two first named positions.

The invention includes various novel features of construction and combinations of parts hereinafter fully described and claimed.

In the accompanying drawings, illustrating my invention: Figure 1, is a plan view 40 of a railway switch structure having my invention applied thereto. Fig. 2, is a vertical section through my improved mechanism, on line 2--2 of Fig. 1. Fig. 3, is a vertical section thereof, on line 3--3 of Fig. 1. Fig. 45 4, is a view of the bottom of the partially rotatable head for setting the mechanism in different positions. Figs. 5, 6 and 7 are plan views of the box at one side of the switch structure with the cover of the box removed, 50 exposing my improved mechanism contained therein, Fig. 5 showing the parts in position to maintain the switch tongue at the track rail side of the switch structure, Fig. 6 showing the parts in position to maintain the 55 switch tongue at the guard rail side of the switch structure, and Fig. 7 showing the

parts in position to maintain the switch tongue in either the position at the track rail side or at the guard rail side of the switch structure.

Referring to the drawings, 4 designates the general framework of the switch structure, on one side of which is formed the track rail 5, and on the other side of which is formed the guard rail 6. Supported on a 60 suitable floor portion of the framework, between the rails 5 and 6 is the switch tongue 7, the heel end 8 of which is pivoted to the framework. The tongue 7 is adapted to occupy a position against the track rail 5, as 65 shown in Fig. 1, to direct car wheels to and from the same; and the tongue is adapted to be moved from the track rail 5 over against the guard rail 6 to form a part thereof and to clear the track rail 5, in the usual manner and for the usual well known purpose. 70

Secured to the framework 4 and forming, in effect, a part thereof, adjacent to one side of the switch tongue 7, is a box 9 adapted to contain my improved switch operating mechanism, as follows: Supported in the bottom of the box 9 is the lower end of a vertical shaft 10 on which is fulcrumed a horizontally-movable lever 11, having two arms 12 and 13. The arm 12 is bifurcated and embraces one end of a link 14. The other end of the link 14 is pivoted, at 15, to a suitable head 16 on the end of a rod 17 which extends from the box 9 through parts of the framework to and through a lug 18 on the 80 bottom of the tongue 7 and is secured thereto by means of nuts 19. The link 14 is connected to the arm 12 of the lever 11 by a pin 20 which is adapted to be inserted into an opening 21 in the arm 12 and a slot 22 85 in the link 14, or into an opening 23 in the arm 12 and an opening 24 in the link 14, as desired for a purpose hereinafter explained. The arm 13 of the lever 11 is provided with a roller 25 which is engaged by a cam 26 90 formed on an arm 27. One end of the arm 27 is pivoted, at 28, to the box 9 and the other end of the arm 27 is engaged by a head or nut 29 on one end of a rod 30 which extends through the arm 27 and through a wall 95 or projection 31 formed in the box 9 and spaced from the arm 27. The other end of the rod 30 is provided with a suitable head 32; and encircling the rod 30 and interposed between and engaging the wall 31 and head 32 is a strong spring 33 which tends to force the cam 26 toward the shaft 10 or fulcrum 100 105 110

of the lever 11. The cam 26 has a high point 34 and two faces or portions 35 and 36 diverging from the high point 34 in directions away from the shaft 10 or fulcrum of the lever 11. The faces 35 and 36 are so arranged with relation to each other and to the pivot 28 and fulcrum of the lever 11 that when the face 35 engages the roller 25, the spring 33 will tend to force the lever 11 in the direction of the arrow in Fig. 5, and that when the face 36 engages the roller 25, the spring 33 will tend to force the lever 11 in the reverse direction, as indicated by the arrow in Fig. 6, for a purpose hereinafter appearing.

In order to turn the lever 11 to set the mechanism in different positions, I provide the upper end of the shaft 10 with a head 37 which is rotatable thereon and which is adapted to turn in a socket in the cover plate 38 for the box 9. The cover plate 38 is secured to the top of the box 9 by suitable cap screws. The bottom of the head 37 is provided with two downwardly-extending projections 39 which are arranged between projections 40 extending upwardly from the top of the lever 11. When the head 37 is turned, the projections 39 will engage the projections 40 and turn the lever 11. Lost motion is provided between the projections 39 and 40 so that the projections 40 may move away from the projections 39 under certain conditions explained later. The top of the head 37 is provided with a slot for the reception of a bar or suitable tool for the purpose of turning the head.

The end of the arm 12 of the lever 11 has a socket 41 formed therein, and the side wall of the box 9 is provided with a projection having a socket 42 formed therein. The lever 11 may be moved to bring the socket 41 into registry with the socket 42 to permit a bar or other tool to be inserted into the two sockets to hold the lever 11 against movement by the spring 33 for a purpose hereinafter explained.

The operation is as follows: When the parts are in the position shown in Figs. 1 to 5, inclusive, the spring 33 tends to force the lever 11 in the direction of the arrow in Fig. 5, causing the pin 20 within the opening 21 to engage the end wall of the slot 22 nearest to the arm 27 and force the rod 17 in the direction of the arrow, Fig. 5, and maintain the switch tongue 7 yieldingly against the track rail 5 in a manner to automatically return the tongue to the track rail, should the tongue be moved therefrom by passing wheel flanges or other means and then released. When the parts are in the position shown in Fig. 6, the spring 33 tends to force the lever 11 in the direction of the arrow, causing the pin 20 within the opening 21 to engage the end wall of the slot 22 farthest from the arm 27 and force the rod

17 in the direction of the arrow, and maintain the switch tongue 7 yieldingly against the guard rail 6 in a manner to automatically return the tongue to the guard rail, should the tongue be moved therefrom by passing wheel flanges or other means and then released. The relation of the cam faces 35 and 36 and roller 25 to the fulcrum of the lever 11, and the relation of the pin 20 and opening 21 to the slot 22 are such that, when the parts are in either of the positions shown in Figs. 5 and 6, the switch tongue 7 will be automatically returned to the rail 5 or the rail 6 from which it is moved and then released, irrespective of the extent of movement of the tongue between the two rails. When however the pin 20 is removed from the opening 21 and slot 22, and is inserted into the openings 23 and 24, the relation of the cam faces 35 and 36 and roller 25 to the fulcrum of the lever 11 and the connection between the lever 11 and link 14 are such that the roller 25 may be moved from one to the other of the faces 35 and 36 and from side to side of the high point 34 when the switch tongue 7 is moved from one to the other of the rails 5 and 6. It will thus be seen that, when the pin 20 connects the lever 11 and link 14, as shown in Fig. 7, the tongue 7 may be held yieldingly in positions 95 against either the rail 5 or the rail 6, to prevent "kicking" etc., in accordance with the position of the roller 25 with respect to high point 34 of the cam 26.

When it is desired to change the position 100 of the lever 11 from one to the other of the positions shown in Figs. 5 and 6, the same may be readily done by inserting a bar into the slot in the head 37 and turning the same, thereby causing the projections 39 to engage the projections 40 and turn the lever 11 until the roller 25 passes the high point of the cam. The initial movement of the lever 11 against the action of the spring 33 will move the pin 20 from the end wall of the slot 22 with which it is engaged until the roller 25 passes the high point 34, when the action of the spring 33 will continue the movement of the lever 11 in the same direction and bring the pin 20 into engagement 115 with the other end wall of the slot 22 and change the position of the switch tongue 7 and hold it yieldingly in its changed position. As the roller 25 leaves the high point 34 of the cam under the action of the spring 33, the projections 40 of the lever 11 will leave the projections 39 of the head 37, due to the lost motion between them, and thus relieve the hand of the operator from the shock of the action of the spring 33 when it comes into play to continue the movement of the lever 11. In the same manner just described, the roller 25 may be moved from side to side of the high point 34 of the cam 26 to set the lever 11 in position to maintain 120

the tongue yieldingly in engagement with either the rail 5 or the rail 6, when the pin 20 connects the lever 11 and link 12, as shown in Fig. 7.

When it is desired to change the pin 20 from one to the other of the slot 22 and opening 24, and when the parts of the mechanism are originally assembled, the lever 11 may be moved against the action 10 of the spring 33 until the socket 41 in the lever comes into registry with the socket 42 in the box 9, and a suit 15 bar may be then inserted into the opening formed by the two sockets, and the bar will hold the lever 11 in a position against the action of the spring 33 and in which the link 14 and parts connected thereto may be freely adjusted relatively to the lever 11 to permit the insertion of the pin 20 either into the 20 opening 21 and slot 22 or into the two openings 23 and 24, as desired.

I claim:

1. In a railway switch mechanism, the combination of supporting means, a movable 25 tongue thereon, a pivoted arm provided with a cam, a spring tending to move said arm, a lever operated by said cam, and connections between said tongue and said lever.

2. In a railway switch mechanism, the combination of supporting means, a movable 30 tongue thereon, a pivoted arm provided with a cam, a rod connected to said arm and extending therefrom and having a head thereon, a spring encircling said rod and interposed between said head and a part of 35 said supporting means and tending to move said arm, a lever operated by said cam, and connections between said tongue and said lever.

3. In a railway switch mechanism, the combination of supporting means, a movable 40 tongue thereon, a pivoted arm provided with a cam, a lever having a part engaged by said cam, said cam having a high point 45 and two portions diverging from the high point in directions away from the fulcrum of the lever, a spring tending to move said arm toward the fulcrum of the lever, and connections between said tongue and said 50 lever.

4. In a railway switch mechanism, the combination of supporting means, a movable 55 tongue thereon, a pivoted arm provided with a cam, a lever having a part engaged by said cam, said cam having a high point 60 and two portions diverging from the high point in directions away from the fulcrum of the lever, a spring tending to move said arm toward the fulcrum of the lever, a part 65 connected to said tongue and having a slot formed therein, and a part carried by said lever and extending into said slot and movable from end to end thereof, said lever being adapted to be forced in opposite directions by the diverging portions of the cam

in different positions of the parts, and said part being forced toward one end of said slot when said lever is forced in one direction and being forced toward the other end of said slot when said lever is forced in the 70 other direction.

5. In a railway switch mechanism, the combination of supporting means, a movable tongue thereon, a pivoted arm provided with a cam, a lever having a part engaged by said cam, said cam having a high point 75 and two portions diverging from the high point in directions away from the fulcrum of the lever, a spring tending to move said arm toward the fulcrum of the lever, 80 said lever adapted to be forced in opposite directions by the diverging portions of the cam in different positions of the parts, a part connected to said tongue, and means whereby said lever may engage said part at 85 two different points.

6. In a railway switch mechanism, the combination of supporting means, a movable tongue thereon, a lever, a spring tending to move said lever around its fulcrum, a part 90 connected to said tongue, and means for connecting said lever to said part at different distances from the fulcrum of the lever.

7. In a railway switch mechanism, the combination of supporting means, a movable 95 tongue thereon, a pivoted arm provided with a cam, a lever having a part engaged by said cam, said cam having a high point and two portions diverging from the high point in directions away from the fulcrum 100 of the lever, a spring tending to move said arm toward the fulcrum of the lever, said lever being adapted to be forced in opposite directions by the diverging portions of the cam in different positions of the parts, a 105 part connected to said tongue, and means whereby said lever may engage said part at three different points.

8. In a railway switch mechanism, the combination of supporting means, a movable 110 tongue thereon, a pivoted arm provided with a cam, a lever having a part engaged by said cam, said cam having a high point and two portions diverging from the high point in directions away from the fulcrum 115 of the lever, a spring tending to move said arm toward the fulcrum of the lever, said lever being adapted to be forced in opposite directions by the diverging portions of the cam in different positions of the parts, a 120 part connected to said tongue, and means whereby said lever may engage said part at three different points, one of said points being nearer to the fulcrum of the lever than the other two points.

9. In a railway switch mechanism, the combination of supporting means, a movable tongue thereon, a pivoted arm provided with a cam, a lever having a part engaged by said cam, said cam having a high point 125

and two portions diverging from the high point in directions away from the fulcrum of the lever, a spring tending to move said arm toward the fulcrum of the lever, said lever being adapted to be forced in opposite directions by the diverging portions of the cam in different positions of the parts, a part connected to said tongue, and means for connecting said lever to said part at different distances from the fulcrum of the

lever, the last named means providing lost motion between the lever and said part when connecting the lever and said part farthest from the fulcrum of the lever.

In testimony whereof I affix my signature 15
in presence of two witnesses.

CHARLES A. ALDEN.
